Des. 202,535

Patented Oct. 12, 1965

202,535

PORTABLE HAIR DRYER

Brian Cooper, 12 Mansfield Place, Ascot, England

Filed July 21, 1964, Ser. No. 80,948

Claims priority, application Great Britain Jan. 24, 1964

Term of patent 14 years

(Cl. D86—10)

FIG. 1.

FIG. 2.

FIG. 3.

FIG. 4.

The essential features of the design reside in the full line portions of the drawing.

I claim:

The ornamental design for a portable hair dryer, as shown and described.
